W. J. KEEP & C. WIPFLER.

COOKING STOVE.

No. 18,251.

Patented Apr. 10, 1888.

UNITED STATES PATENT OFFICE.

WILLIAM J. KEEP AND CHARLES WIPFLER, OF DETROIT, MICHIGAN, ASSIGNEES TO THE MICHIGAN STOVE COMPANY, OF SAME PLACE.

DESIGN FOR A COOKING-STOVE.

SPECIFICATION forming part of Design No. 18,251, dated April 10, 1888.

Application filed June 22, 1887. Serial No. 242,187. Term of patent 7 years.

To all whom it may concern:

Be it known that we, WILLIAM J. KEEP and CHARLES WIPFLER, both citizens of the United States, residing at Detroit, in the county of Wayne and State of Michigan, have invented certain new and useful Improvements in a Design for a Stove, of which the following is a specification, reference being had therein to the accompanying drawing.

10 This design is for a wood cook stove having a reservoir and high shelf.

Referring to the appended photograph, A indicates the legs, each having its upper part ornamented by a coil or scroll, a, below which is a representation of fringe, a', and its toe terminates in a solid scroll. Each of these legs, it will be seen, is narrower near the top than at a point on a line drawn horizontally across the bottom of the scroll a. Between 15 these legs is a base, B, ornamented with a series of scrolls gradually diminishing in size 20 toward the center.

The oven-door is of peculiar shape, having curved edges at the top, bottom, and rear, and sharp edges at front. It is ornamented by a central ornament, C, which is not broadly claimed here, as it forms the basis of a claim made in another application made by us. This ornament consists of a raised panel. To 25 the left of the central ornament, and immediately adjoining the same, is another ornament, c, of substantially triangular form, which also is not broadly claimed here, for the same reason. This ornament consists of a rosette 30 at one corner and scrolls extending from one of the other corners to the third corner. Partially surrounding the rosette are six openings formed in the body of the scroll-work. The lower forward corner of the door is ornamented by a series of scrolls, C', arranged in 35 a substantially triangular form, the central end of one of the scrolls terminating in a non-descript head. The upper rear corner of the door is also ornamented with scrolls c'', extending along the top and partially down the rear side.

The fire-door D has a central ornament, d, consisting of a rosette surrounded by scrolls. Each side of the door is also ornamented by 40 scrolls running from the top to the bottom.

50 The door E at the side of the reservoir is

ornamented with a band, e, representing fringe with portions hanging loose at each end, above which are two rosettes of different sizes, which rosettes are partially surrounded by 55 leaves. Below the fringe is a circular ornament, the border of which forms a fancifully-shaped letter G, inside of which are scrolls. At the rear of this ornament is a large rosette, and in front of the same, on a lower plane, is 60 a smaller one, the two being connected by a drooping ribbon.

Resting upon the stove is the pipe H, provided with an apertured projection, h, and the wings h'. Behind the projection h is shown 65 a pouch-bracket, I, having a curved and inclined under side.

What we claim as new is—

1. A design for a stove, comprising the leg-base and legs, the body surmounting said legs 70 and base, the parallel-sided reservoir at the rear of the body, and the pipe at right angles to the length of the body, ornamented over said reservoir by the curved pouch and surrounded by a shelf, all having the ornamentation shown. 75

2. In a design for a stove, the pipe H, having an ornamented rectangular projection in front, and at the rear a pouch having a segmental curve, as shown. 80

3. In a design for a stove, the fire-door having the surface ornamentation, comprising a rosette centrally set within oppositely-disposed scrolls, provided with vertical edge ornaments, as set forth. 85

4. In a design for a stove, the oven-door having the shape shown, with its front edges at a sharp angle with the body, and the top, bottom, and rear edges curved, as shown.

5. In a design for a stove, a leg having a 90 projecting scroll at its upper part partially surrounded by a fringe-like ornament and terminating in a scroll-like toe, as shown.

In testimony whereof we affix our signatures, in presence of two witnesses, this 15th day of 95 June, 1887.

WILLIAM J. KEEP.
CHARLES WIPFLER.

Witnesses:

GEO. L. RENO,
E. H. BOND.
